UNITED STATES PATENT OFFICE.

RICHARD W. MAEDLER, OF FORT LEE, NEW JERSEY, ASSIGNOR TO DANIEL P. BERGHEIMER, OF NEW YORK, N. Y.

CABINET.

1,367,410.

Specification of Letters Patent.

Patented Feb. 1, 1921.

Application filed April 2, 1920. Serial No. 370,732.

To all whom it may concern:

Be it known that I, RICHARD W. MAEDLER, a citizen of the United States, residing at Fort Lee, in the county of Bergen and State 5 of New Jersey, have invented new and useful Improvements in Cabinets, of which the following is a specification.

This invention relates to improvements in phonograph cabinets, and aims to provide 10 a cabinet which is combined with a table for use where economy of space is necessary and to provide an article of furniture of neat and attractive appearance.

Another object of the invention is the 15 provision of a phonograph cabinet in which the instrument is normally housed within an inclosure or compartment constructed in connection with the table, the instrument being normally concealed and mounted for 20 sliding movement, to permit of positioning the record and to permit access to a record compartment also provided in the inclosure.

A further object of the invention is the 25 provision of means for permitting the escape of the sound through a horn, which is directed outward through one end of the cabinet, escaping through the end of the inclosure, producing a rich tone quality.

Other objects and advantages of the 30 invention will appear as the following description is read in connection with the accompanying drawings,

In the drawings:—

Figure 1 is a perspective view of a combined table and phonograph cabinet, showing the same in closed position.

Fig. 2 is an end view of the cabinet partly broken away.

Fig. 3 is a transverse sectional view of 40 the cabinet taken longitudinally of an instrument drawer.

Fig. 4 is a side elevation in section with the drawer extended for the application of a record or winding the spring of the instrument.

Referring to the drawings in detail, wherein like characters of reference denote corresponding parts, the invention comprises a table which includes a top 10 and the supporting legs 11. Beneath the top 10, the table is inclosed by front panels 12, rear panels 13, and end panels 14, the panels at one end of the table upon both the front and rear sides thereof, being formed by the ends 15 of a transversely slidable drawer

16. This drawer is capable of being opened, from either side of the table for a predetermined distance. This distance is limited by stops 17, which contact with a stationary portion of the panels 12 and 13, but are capable of movement so as to permit of the withdrawal of the drawer when necessary or desirous. The panels and drawer just described provide an inclosure or cabinet for housing a phonograph and for this purpose, the drawer 16 is divided by means of a partition 18 into separate compartments 19 and 20. The compartment 19 is for the purpose of receiving a phonograph instrument 21, the depth of the drawer being 70 greater than the height of the instrument, so that the latter will be contained wholly within the drawer to prevent damage and permit the drawer to close. For the purpose of adjusting and removing a record, 75 one side of the drawer is cut away as indicated at 22, this cut away portion also permitting of securing and removing the usual needle points.

The drawer is further provided upon this 80 side with an opening 23 and when in closed position, this opening will register with an opening 24, which is located in the small end of a horn 25. This horn is located within the cabinet and extends from the side of the drawer outward toward the end wall 14, the sound escaping through the scroll work at this end of the cabinet. An additional opening 26 is provided in the side of the drawer through which the end of the crank 90 arm 27 extends for the purpose of winding the spring of the instrument, this crank arm being removable to permit the drawer to close.

The compartment 20 which is provided in the drawer is designed to receive records for use in connection with the instrument and the side of the drawer is cut away as indicated at 28 for convenience in removing the record.

In addition to the record space provided in the drawer, that portion of the cabinet through which the horn 25 extends, is provided upon each side of the horn with a hinged compartment 29, which is closed by a panel 30, the latter being hinged along its bottom edge and capable of being swung outward to permit of the removal and insertion of the records.

In the use of the invention, the drawer is 110

pulled out at one end the distance being regulated by one of the stops 17, which is sufficient to permit a record to be placed in position. The spring may be then wound 5 and the drawer closed, the sound from the instrument striking the undersurface of the top of the table and passing out through the ends 14 which are provided with suitable openings for this purpose, these ends 10 being herein shown as formed of scroll work.

The invention is susceptible of various changes in form, proportions and minor details of construction and the right is herein 15 reserved to make such changes as properly fall within the scope of the appended claims.

Having thus described my invention what I claim as new is:—

20 1. The combination with a table having an inclosure beneath the top, of a drawer slidably mounted in said inclosure, and capable of being opened from either end, a

partition dividing the drawer into a phonograph compartment and a record compartment, said drawer being of greater depth 25 than the height of the phonograph to protect the latter and having one side wall of each compartment cut away to facilitate the removal of the records from the record 30 compartment and the application and removal of the records from the phonograph, and a sound exit located at one side of the drawer.

2. The combination with a table having a 35 compartment located beneath the top, of a drawer slidably mounted in said compartment and said drawer having an opening in one side wall, a phonograph within the drawer and a horn located within the compartment with the small end of the horn 40 registering with the opening in the drawer when the latter is closed.

* In testimony whereof I affix my signature.

RICHARD W. MAEDLER.
